UNITED STATES PATENT OFFICE.

HANS PEDERSON, OF COUPLAND, TEXAS.

EARTH-AUGER.

SPECIFICATION forming part of Letters Patent No. 553,660, dated January 28, 1896.

Application filed April 6, 1894. Serial No. 506,629. (No model.)

To all whom it may concern:

Be it known that I, HANS PEDERSON, a citizen of the United States, residing at Coupland, in the county of Williamson and State 5 of Texas, have invented a new and useful Earth-Auger, of which the following is a specification.

My invention relates to earth-augers, and particularly to those designed for digging 10 post-holes, and the objects in view are to provide an improved auger for the purpose named which shall have a lateral, in contradistinction to a horizontal, cutting-edge and a continuous cutting-edge from its point to its top, said 15 cutting-edge receding continuously and uniformly from the axis of rotation of the tool, whereby it cuts from the center outward and gradually widens or increases the diameter of the hole at any given point until this point 20 is reached by the periphery of the ears or basin at the top of the bit, and, furthermore, to provide means for packing or smoothing the sides of the hole.

Further objects and advantages of the invention 25 will appear from the following description, and the novel features thereof will be particularly pointed out in the appended claim.

In the drawings, Figure 1 is a perspective 30 view of an auger embodying my invention. Fig. 2 is a side view showing the auger from a position indicated by the arrow in Fig. 1. Fig. 3 is a plan view, a dotted line being arranged to inclose the blade to show the divergence of the cutting-edge from a true circle. Fig. 4 is a transverse inverted section 35 on the line 4-4 of Fig. 2.

Similar numerals of reference indicate corresponding parts in all the figures of the drawings.

The staff 1 of the improved auger is preferably formed integral with the bit or head 2, said bit or head being reduced to a feeding-point 3 at its lower end and having a plurality 45 of continuous spirally-disposed cutting-edges 4, which, starting at the point 3, recede continuously and uniformly from the axis or center of rotation of the bit until they reach the points 5 at the outer extremities of the radial edges 6 in the plane of the top of the bit.

These radial edges 6 are spaced from the portion of the cutting-edges which extend there-

under to form passages 7, through which the earth passes in rising to the basin 8, formed by the diametrically-opposite horizontally-disposed ears 9 and 10. The portion 11 of the cutting-edge which is disposed above the plane of the bottom of said basin, and which forms the boundary of the basin, is upturned to occupy a substantially vertical position, 60 whereby its outer convex surface serves to compress the surfaces of the sides of the hole as the auger descends, and whereby during the withdrawal of the tool from the hole any loose earth which may be detached is received 65 by the basin. The feeding-point 3 is disposed at such an angle to the axis of rotation as to feed positively and at a rate corresponding with the cutting capacity of the continuous edges. 70

The spiral disposition of the surfaces of the blades causes the loosened or detached earth to be fed upward upon the inclined surfaces until it reaches the plane of the basin in which it is retained to facilitate removal from the 75 hole.

The auger is preferably constructed of diametrically-opposite blades, as shown in the drawings, whereby the opposite cutting-edges operate upon diametrically-opposite portions 80 of the hole, thus equalizing the strain and causing the tool to operate uniformly.

The special advantage of the improved form of auger resides in the facility with which it cuts the earth and in the fact that the previously-cut earth readily yields to the pressure of the newly-cut earth to provide space for its reception. It is obvious that the spirally-disposed edge forms a shearing cut, in that it is disposed, at any given point, at an inclination to the plane of rotation, and while the previously-cut earth is being forced upward upon the inclined faces of the blades the edges are cutting laterally and drawing the earth inward toward the center of the auger to 90 cause the upward pressure by which said previously-cut earth is being elevated. In other words, the tool operates to clear its blades continuously during rotation and thus, by forming a passage for the escape of the 95 earth, facilitates the clearing of the cutting-edges. 100

Having described my invention, I claim—
As an improved article of manufacture, the

herein shown and described earth auger, comprising a staff and bit integrally formed, the bit comprising two diametrically opposite blades uniting at their lower ends to form a feeding point and terminating at their upper ends in opposite horizontally-disposed ears which unitedly form an earth basin, and said blades gradually and uniformly receding or converging from the earth basin to the feeding point and extending in a spiral direction, the outer cutting edge portions of the said

blades curving forwardly, and the upper edge portions thereof being upturned and convexed on their outer surfaces, substantially as described for the purpose set forth.

In testimony that I claim the foregoing as my own I have hereto affixed my signature in the presence of two witnesses.

HANS PEDERSON.
